UNITED STATES PATENT OFFICE.

CIPRIANO VISCHE, OF GENOA, ITALY.

CINEMATOGRAPHIC APPARATUS FOR THE PERFORMANCE OF MUSICAL FILMS.

Application filed April 4, 1921. Serial No. 458,597.

(GRANTED UNDER THE PROVISIONS OF THE ACT OF MARCH 3, 1921, 41 STAT. L., 1313.)

To all whom it may concern:

Be it known that I, CIPRIANO VISCHE, a subject of the King of Italy, and residing at Genoa, Italy, have invented certain new and 5 useful Improvements in Cinematographic Apparatus for the Performance of Musical Films (for which I have filed applications in Italy, on Dec. 24, 1913, Pat. No. 139,175; in Germany, on April 9, 1920; in England, 10 on April 9, 1921; in Austria, on April 6, 1921; in Switzerland, on April 8, 1921; in France, on April 9, 1921; in Belgium, on April 11, 1921; in Spain, on May 3, 1921; and in Italy, on April 8, 1921), of which the 15 following is a specification.

The invention relates to improvements in cinematographic apparatus by means of which in the apparatus for taking or projecting moving pictures the time of the music 20 accompanying the talking or the projection of the films is simultaneously and synchronously registered with the pictures on the film and also to a device by means of which the signs so produced on the negative 25 or the positive film are utilized to effect the synchronous indication of the time to the band master who directs the music accompanying the projection of the film.

This invention substantially consists in 30 providing the cinematograph apparatus with electro-mechanical means such that, by beating the time of the music accompanying the taking or the projection of the film, the closure of electric circuits effects the production on the running film of consecutive punctures or light-effects on the negative film or punctures only on the positive film, the said punctures or light effects on the negative film or the punctures on the positive film 35 being used to make holes in corresponding positions on the positive film and the series of holes thus prepared in the positive film being used to effect the consecutive closure of circuits for the indication of the 40 time to the band master, whilst the positive film is run over a specially constructed roll of the projection apparatus.

In order that the invention may be clearly understood reference is made to the accompanying drawings which illustrate, by way of example, two embodiments of the inventions and in which:—

Fig. 1 is a vertical sectional view of the

picture taking apparatus with puncture device for the negative film in connection with 55 a key switch on the music stand;

Fig. 2 shows the projection apparatus in a partial view in connection with the time indicator on the music stand;

Fig. 3 shows a top view of the puncture 60 device on the picture taking apparatus;

Fig. 4 is a section according to the line 4—4 of Fig. 3;

Fig. 5 is a section according to the line 5—5 of Fig. 3;

Figs. 6 and 7 show respectively a vertical and a horizontal section of the key switch on the music stand;

Fig. 8 is a front view of a part of the projection apparatus;

Fig. 9 is a top view of Fig. 8;

Fig. 10 is a section according to line 10—10 of Fig. 9;

Fig. 11 is a section according to line 11—11 of Fig. 10;

Fig. 12 is a section according to line 12—12 of Fig. 10;

Fig. 13 and Fig. 14 are two views taken under a right angle of the time indicator on the music stand;

Figs. 15, 16 and 17 are respectively an upper, frontal and side view of the time meter on the music stand;

Fig. 18 is a vertical section according to the line 18—18 of Fig. 19 and Fig. 19 a 85 horizontal section of Fig. 18 both of said Figs. 18 and 19 referring to a further device for the registration of the time on the negative film, in which the same is subjected to consecutive light effects instead of punctures. 90

In these figures in which the same numbers indicate the same parts, the film runs in the picture taking apparatus from the roll 1 to the easing 2 supplied with the puncture device; and from thence to the position 95 where it is exposed to the photographic effect and is finally wound up on drum 3. The film is guided within the casing 2 by the pair of rolls 4—4' immediately after its entrance in the casing and by a corresponding pair of rolls 5—5' before leaving the casing 2. Between these two pairs of rolls the film runs over a horizontal path, over which it is guided by the lower guides 6, the lateral guides 7, the shoes 8 and the slightly curved 100 springs 9 arranged under the shoes. By 105

means of the springs 9, the shoes 8 bear resiliently against the film in order to allow of the passage of joints in the film. To one side of the film are arranged the two electromagnets 10 and 10', electrically connected with the two plate terminals 11 and 11' and further connected through the plate terminals 12-12' and columns 13-13' with the plug contact socket 14. The electromagnets 10-10' are provided with a common armature 15, which is pivotally mounted upon the pin 16. Perpendicularly to the horizontal path of the film is arranged a rod 17, upon which the armature 15 bears; this rod on its turn bears at its lower end on the one end of a double arm lever 18 which is fulcrumed at 19. Upon the other end of the lever 18 bears by means of a roller 20 the lever 21 slidably mounted in a member 26 which in turn is pivotally mounted on the pin 22. The upper arm of the lever 21 is provided with a needle which is arranged so as to penetrate the path of the film through a slot 6' in the guides 6. The lower arm of the lever 21 bears with its roller 20 under the pressure of the spiral spring 21' on the curved guide 23 of the lever 18. If a closure of the circuit takes place in the puncture device on account of the attraction of the armature 15 by the electromagnets 10-10', the lever 18 under the push of the rod 17 will displace the lever 21 from its position as shown in Fig. 5 towards the top, whereby the needle will effect in the moving film an almost invisible hole. The point of the needle penetrating the film will be pulled along by the film for a certain length of the path, the lever 21 sustaining then a rotation around the pin 22 in a second end position during which rotation on account of the travel of the roller 20 upon the curved guide 23, the needle will gradually be drawn back from the film. The positive film may be punctured during a preliminary projection by the same apparatus in which case the punctures will be used for making holes in the film in positions corresponding to said punctures and if necessary these holes will be displaced so as to be positioned on the nearest division line of the film. As soon as the lever 21 reaches this second end position it will be at once returned to its former position by means of the spring 24, so as to be ready for a new puncture, as soon as a new closure of the circuit takes place. By introducing the plug contact in the sockets 14 and 14' the circuit of the puncture device of the film is put in connection with the circuit of the key switch on the music stand.

The key switch Figs. 6 and 7 comprises within the casing 25 the metallic plate 26, upon which are arranged the terminal 27 and the insulated plate terminal 28, which latter in its turn is in conductive connection with the terminal 29 of the receptacle 30 containing mercury. A lever 31 comprising parallel members rotatably arranged upon the shaft 32 and connected at one end by the key 34 engages by means of the free end of the inner arm of one member 31 the inner 70 arm of the lever 35, while such latter lever has on the free end of its outer arm an adjustable steel or platinum point 36. The shaft 32 is supported in the two plates 26 and 33. 37 is a clip provided with regulating screws, allowing to regulate the depth of immersion of the point 36 within the mercury. Springs 38 arranged around the shaft 32 normally retain the key 34 in an elevated position. 39 is a spring, which tends to 80 cause the lever 35 to rotate for effecting the immersion of the point 36 in the mercury. By beating on the key 34, the point 36 will immerse in the mercury of the receptacle 30, closing the circuit in the key switch and therefore also of the puncture device causing the puncture of a hole in the running negative film. The film thus provided with holes will be laid along the positive film and as many holes made in the positive film as are 90 punctures in the negative film. These holes are if necessary displaced on the positive film so that each hole takes its position upon the nearest division line of the film square. The film thus perforated is then conducted over 95 a toothed drum 40 and is held in contact with the surface thereof by means of the three counter-rolls 41. The drum 40 put in rotation by the movement of the film is freely supported on the fixed shaft 42. With this shaft 42 are also associated the two columns 43, supporting the member 44, by means of which the three counter rolls 41 are pressed against the drum 40. The drum is provided on its circumference with two 100 rows of teeth 45 and exactly thirty-two for each row and between these two rows of teeth with eight holes 46, which are equally spaced over the circumference of the drum, each hole being situated between two teeth. 110 In applying the film on this drum the division lines of the photogram will always correspond with the holes 46 of the drum. Radially arranged within the drum and in alignment with the holes 46 are arranged 115 small pistons 47 having a radial travel within these holes; such pistons are pressed outwardly by spiral springs 48. These pistons during part of the rotation of the drum 40 are positively guided upon a spiral band 49 120 and are disengaged from this band during the remaining part of the rotation. Each piston 47 is provided with a contact spring 50, which at a certain outwardly radial displacement of the piston contacts with a corresponding spring 51 situated in the same plane across the axis of the drum. The springs 51 are fastened on a metal band 52, insulated from the drum by an insulating annular piece 53. The metal band 52 is in 125

conductive connection by means of the spiral have to be applied on the projection apparatus.
 spring 58 and brush 59 with the sleeve 60 arranged on the shaft 42, so as to be insulated from this shaft. 61 is an electric circuit 5 wire connected with sleeve 60 and arranged in a central bore of the shaft 42; 62 is a second circuit wire connecting with a terminal situated on the columns 43. The circuit wires 61 and 62 in the circuit of which is inserted the electric battery 59 (Fig. 18), connect with a double electromagnet 55 provided with an armature 54 which is attracted by the magnets during the closure of the circuit and this attraction effecting a beating 10 on an adapted sounding board thereby producing a well perceptible sound indicating the time. During the part of the travel of the pistons in which they are disengaged from the band 49, they will slightly adhere 15 against the film. If now a hole of the film comes opposite a hole of the drum, the piston will penetrate the film and reach its most extreme radial position and thus close the electric circuit. If the piston disengaged 20 from the band 49, does not encounter a film hole, the same will be kept in its radial position by the film itself and during the further rotation of the drum be reengaged by the band 49.

30 In closing the circuit through the wires 61 and 62 the armature 54 through the wires 63 and 64 closes a further circuit, that is the circuit of the time meter, by the displacement of the rod 56, the two poles 57 being 35 brought in contact with each other. When a closure of current takes place in the conductors 63 and 64 the armature 66 of the electromagnet 65 (Figs. 15, 16 and 17) is attracted turning about its pivot 67, whilst 40 the lever 68, engaging with a tooth upon the circumference of the wheel 69, rotates this wheel for one tooth at each closure of circuit. This rotation causes the displacement of a number on the drum 70, which has on 45 its periphery a continuous series of numbers, which numbers are also applied in a corresponding way to the film. The time meter is besides constructed in the manner that any multiple number of 10 is also continually registered. The purpose of the 50 time meter is to avoid the band master through inattention losing the time; and if this should happen to allow the band master to regain rapidly his orientation. 55 When a rupture of the film in the cabin occurs, the band master will have time to communicate with the machinist and will be able to accompany the projection with the correct music without delay. The puncture device 60 can also serve for the synchronous time registration by means of punctures produced in the picture film during a preliminary projection during which the music is played while the conductor beats time on the key 34. 65 In the latter case the puncture device will

have to be applied on the projection apparatus. The device shown in Fig. 18 and Fig. 19 serves for the synchronous registration of the time on a negative film by means of a 70 light effect.

According to these figures within the box 71 of the picture taking apparatus are arranged in the same manner as within the casing 2, the lower guides 6, the lateral guides 7, the shoes 8 and the springs 9. One of these shoes is provided with a hole 72. A funnel arrangement made in the two pieces 73 and 74 with the insertion of a velvet packing between these pieces is arranged 80 over the hole 72 and connects towards the outside with the wall of the casing 71. A slide 75 is coupled with the armature 76 which latter one is actuated by the electromagnet 77. The slide on every closure of 85 the circuit taking place at each time beating of the band master, will bring into correspondence its opening with the opening 72, whereby a ray of light will project on the edge of the negative film, which marks will 90 be further utilized in a corresponding manner as the punctures produced by the puncture device.

It is understood that the band master is always directing musical indications on the 95 film by beating the time during either the taking of the negative film or a preliminary projection of the positive film, and this performance of directing the music will also have to be followed during the projection of 100 the film.

I claim:—

1. Improvements in cinematographic apparatus adapted to obtain in the taking of moving pictures, the synchronous contemporaneous registration with the pictures on the film, of the time of the music accompanying the taking of the pictures, including in combination, a picture taking apparatus including a film, a puncture device in 105 said apparatus and associated with the film, an electro-magnet associated with the puncture device, and an electric key including a switch adapted to be mounted on the music stand of the band master and arranged 110 in circuit with the armature so that the band master during the taking of the moving pictures, by continually beating the time of the music on the key effects the closure of the circuit in the switch, which action, 115 through the electro-magnet operates the puncture device in the picture taking apparatus so that at every time beating there corresponds a hole in the running negative 120 film.

2. Improvements in cinematographic apparatus adapted to obtain in projecting moving pictures the synchronous contemporaneous indication of the time of the music accompanying the moving pictures in utilizing 125

ing a positive film in which holes have been applied in correspondence with the punctures of the negative film prepared according to claim 1, including in combination a drum over which the film in the projection apparatus is conducted, a series of resiliently mounted pistons arranged radially and within a plane normal to the axis of the drum, each of said pistons, during the travel 10 of the positive film over the drum, and when coinciding with one of the film holes, being adapted to penetrate such holes and move to its extreme radial position, a sound producing device adapted to be arranged on the 15 music stand of the band master and including an armature arranged in circuit with the drum, and coacting circuit closures carried by the drum and pistons and operable when the pistons move to their extreme 20 radial positions to effect a closure of the circuit and thereby influence the electro-magnet so that its armature is caused at each closure of the said circuit to beat on the base forming a part of the sound producing 25 device to indicate the time.

2. A device according to claim 2, in which a shunt circuit is arranged in the circuit of the projection apparatus and the time indicator on the music stand and designed to be 30 closed at every closure of the aforesaid main circuit, and a time meter operated by the shunt circuit indicating in consecutive numbers the numbers of the time and which num-

bers are also adapted to be applied in a corresponding way on the film. 35

4. A device according to claim 1, characterized in this, that by the time beating of the band master in the running film of the picture taking apparatus, light effects are produced on the film instead of punctures, 40 such light effects being utilized in the same way as the punctures for the preparation of the positive film.

5. An apparatus as defined by claim 1, in which, the film in the picture taking apparatus is conducted in a horizontal path with relation to the puncture device, said device including a double arm lever rotatable in the plane of the running film, a point on the upper end of the lever adapted to move 45 linearly relatively to the pivotal point of the lever, said point being pushed upwards at every closure of circuit by the key switch so as to penetrate the running film, the point on account of the rotation of the lever 50 being gradually drawn back from the film and means for automatically returning the lever and point to the original position in order to be ready for a consecutive puncture. 55

In testimony whereof I have signed my name to this specification. 60
